UNITED STATES PATENT OFFICE

103,323

DESIGN FOR A MILL BUILDING

Henry Janssen, Wyomissing, Pa., assignor to Textile Machine Works, Wyomissing, Pa., a corporation of Pennsylvania

Application December 30, 1936, Serial No. 66,809

Term of patent 14 years

To all whom it may concern:

Be it known that I, Henry Janssen, a citizen of the United States of America, residing at Wyomissing, in the county of Berks and State of Pennsylvania, have invented a new, original, and ornamental Design for a Mill Building, of which the following is a specification, reference being had to the accompanying drawings, forming part thereof.

Figure 1 is a perspective view of a mill building showing my new design;

Fig. 2 is a front elevational view of the building shown in Fig. 1;

Fig. 3 is a side elevational view of the building

shown in Fig. 1, in which a central portion has been removed to permit showing of the building on a larger scale;

Fig. 4 is an enlarged elevational view of one of the entrances to the mill building, shown in Fig. 2; and

Fig. 5 is a top plan view showing the mill building on a slightly reduced scale as compared to Fig. 3.

I claim:

The ornamental design for a mill building, as shown and described.

HENRY JANSSEN.
